UNITED STATES PATENT OFFICE.

JOHN L. FARNES, OF REXBURG, IDAHO.

ROTARY ENGINE.

SPECIFICATION forming part of Letters Patent No. 632,404, dated September 5, 1899.

Application filed December 8, 1898. Serial No. 698,676. (No model.)

To all whom it may concern:

Be it known that I, JOHN L. FARNES, a citizen of the United States, residing at Rexburg, in the county of Fremont and State of Idaho, have invented certain new and useful Improvements in Rotary Engines; and I do hereby declare the following to be a full, clear, and exact description of the invention, such as will enable others skilled in the art to which it appertains to make and use the same.

My invention relates to improvements in rotary engines; and it consists in certain novel features of construction and combinations of parts, as will be hereinafter more fully described and claimed.

In the accompanying drawings, illustrating the invention, Figure 1 is a side elevational view of my improved rotary engine. Fig. 2 is an end elevation of the same. Fig. 3 is a cross-section, and Fig. 4 is a vertical longitudinal section.

Referring now more particularly to the said drawings, A represents a base or bed plate, and B a cylinder mounted thereon. This cylinder is cast integrally with a base-piece C, bolted or otherwise suitably secured to the bed-plate and formed at each end with flanges d, to which the heads D are bolted. The central portion E of the cylinder is enlarged and formed at its upper end with a steam-chest f, having a detachable face-plate g. This face-plate may be readily and conveniently removed when it is desired to get access to the steam-chest and induction-pipes for the purpose of cleaning, repairing, or replacing defective or worn-out parts.

The rotary piston-wheel H is mounted on a shaft I, journaled in bearings j on the cylinder-heads D, and carries at one end a fly-wheel J. The opposite end of the shaft may be provided with a belt-wheel or pulley for transmitting power. Automatic oil-cups j' of suitable construction are provided to feed oil to the bearings.

The piston-wheel fits steam-tight in the cylinder B and is formed with an annular series of steam-pockets k, which are beveled or rounded off at their outer side and end edges k' to facilitate the ingress and egress of steam and prevent condensation by the direct impingement of the steam against an angular surface. Steam is fed to these pockets through

two oppositely-disposed channels or passages i i', which are in communication at their upperends with two steam-induction pipes m m', leading from the steam-chest. The lower ends of said channels or passages open into the piston-chamber and are adapted to supply steam simultaneously to pockets at diametrically opposite sides of the wheel, the arrangement being such that steam from one passage impinges directly against the bottom of one pocket, while the steam from the opposite channel impinges against the top of the other pocket.

Live steam enters the chest f from the main supply-pipe through an inverted-U-shaped union-pipe N, the parallel tubular arms n of which are fitted steam-tight in the face-plate g, in line with the induction-pipes m m'. A slide-valve O controls the passage of steam to said pipes m m' and is connected at its outer end to a pivoted handle o'.

At the lower end of the cylinder is an exhaust-passage p, which leads to an exhaust-pipe q, tapped into the base C, and at the upper end of the cylinder, below the steam-chest, is an exhaust-steam chamber r, through which the lower ends of the induction-pipes m m' pass. Leading from said chamber is an exhaust-passage s, which extends around the side of the cylinder and communicates at its lower end with an exhaust-pipe t. By this construction it will be seen that the steam exhausting from the pockets on the descending side of the piston discharges into the passage p, while the steam from the pockets on the ascending side of the piston first discharges into the chamber r and thence passes into the passage s. The pipes m m' being in contact with the steam in chamber r are maintained in a highly-heated state, which serves to retard condensation of the live steam passing therethrough.

From the above description, taken in connection with the accompanying drawings, the construction and mode of operation of my improved rotary engine will be apparent. It will be seen that the invention provides a motor of this type which is simple and effective in construction and embodies certain advantages due to its construction alone.

Having thus fully described my invention, what I claim as new and useful, and desire to

secure by Letters Patent of the United States,
is—

1. A rotary engine comprising in combination,
5 a cylinder provided with a steam-chest,
and an exhaust-steam chamber below the
same and in communication with an exhaust-
passage, a piston-wheel mounted to revolve
in said cylinder, duplicate steam-induction
10 passages leading to said wheel, duplicate
steam-induction pipes leading from the chest
through said exhaust-steam chamber to the
induction-passages, a detachable face-plate
on the steam-chest, and a steam-supply pipe
15 connected with said face-plate, substantially
as described.

2. A rotary engine comprising, in combina-
tion, a cylinder provided with a steam-chest
and a steam-exhaust chamber below the same,
two exhaust-pipes, an eduction-passage lead-

ing from said exhaust-chamber to one of the 20
exhaust-pipes, a second eduction-passage at
the lower end of the cylinder and leading to
the other exhaust-pipe, a piston-wheel hav-
ing an annular series of steam-pockets, du-
plicate steam-induction passages adapted to 25
supply steam to said pockets, duplicate steam-
induction pipes leading from the steam-chest
through said exhaust-steam chamber to the
induction-passages, a detachable face-plate
30 on the steam-chest, and a steam-supply pipe
connected with said face-plate, substantially
as described.

In testimony whereof I affix my signature
in presence of two witnesses.

JOHN L. FARNES.
